DUST SPRAYING DEVICE

William H. Rose, Jersey City, N. J.

Application September 3, 1937, Serial No. 163,904

5 Claims. (Cl. 43—147)

My invention relates to powder-spraying devices and refers particularly to devices of this character in which the finer particles of the powder are automatically separated from the 5 larger particles, the finer particles being emitted in the form of a spray, while the larger particles are retained in the powder container.

As powders are sprayed with the object of covering as large an area as is possible with a given 10 quantity of powder, it is evident that the amount so covered is dependent upon the fineness of the sprayed powder.

In the employment of insecticidal powders, it is essential that a maximum number of insects 15 or a maximum amount of foliage must be contacted in order to produce the maximum results, and hence the efficiency and economy of such powders are dependent upon the fineness of the powder employed.

20 In the usually employed powder-sprays, or powder guns, the powder is placed in a receptacle and forced outwardly in the form of a spray by means of an air current, the spray consisting of the entire powder mass of large and small particles.

25 The larger particles act adversely to the proper efficiency of the spray, as their action upon the lighter particles materially reduces the distance to which the material may be sprayed, reduces 30 the breadth of the spray, prevents a proper distribution of the smaller particles, and, further, because the larger particles present a smaller contact surface than do smaller particles for the same amount of powder material.

35 It is evident, therefore, that superior results would be obtained if the finer particles only were used for spraying purposes.

I have overcome the difficulty of separating the finer particles from the larger particles by constructing a device in which this separation is 40 automatically accomplished during the spraying process and in which the finer particles are contained within the spray and the larger ones retained in the powder container.

45 The novelty, usefulness and advantages of my device will be evident upon a consideration of my specification and its accompanying drawing, in which similar parts are designated by similar numerals.

50 Figure 1 is a broken vertical cross section of one form of the device of my invention.

Figure 2 is a front view of the upper portion of the device of Figure 1.

55 Figure 3 is a section taken on the line 3—3 of Figure 1.

Figure 4 is a fragmentary vertical section of a modified form of the device of my invention.

Figure 5 is a fragmentary front view of the device of Figure 4.

The particular form of the device of my invention illustrated in Figures 1 to 3 comprises a casing 10 having a closed end 11 through which there is a central opening 12 and a closed end 13 having a curved formation with a centrally positioned concave portion 14 through which is an 10 opening 15. A longitudinally movable plunger 16 consists of the metal disk 16, the leather, or rubber, washer 17 and the metal member 18, the latter being adapted to maintain the disk 16 in contact with the inner face of casing 10 and to 15 maintain it in proper form during the operating process. A plunger rod 19 is attached to the plunger member and extends outwardly through the opening 12 of the end 11 and has a handle 20 attached thereto. Fixedly attached to the inner 20 face of the casing 10 is a metal annular member 21 having openings 22, 22 therein, which are covered by the flexible dust impervious member 23 attached to the member 21 by means of the rivet 25 24.

The device of my invention is not limited to the particular construction of powder gun above described, this form being illustrated simply as a means of showing and describing the dust forming and spraying elements of my device.

A container cover 25 is fixedly attached to the forward and under side of the powder gun and has a threaded downwardly extended curtain flange 26 adapted to be removably attached to the threaded neck 27 of the powder container 28.

The cover 25 has an opening 29 through which is passed the tube 30, the upper end of which is in alignment with the opening 15 of the end 13 and the lower end of which terminates in the upper portion of the powder container 28 and above the top of the powder 31 within the container indicated by the line 32.

The cover 25 has another opening 33 and the casing 10 has an opening 34 through which is 45 passed the tube 35, the upper end of which terminates in the lower portion of the chamber 36 formed by the end 13 and the member 21, the lower end of the tube 35 terminating a short distance from the bottom of the powder container 28. 50

The operation of the device is as follows: When the plunger is forced inwardly within the casing, the valve 23 covers the openings 22, 22 and the air within the chamber 36 is forced through the opening 15 of the end 13 and through the tube 35

35 into the lower portion of the powder 31 within the container 28.

5 The air forced through the tube 35 agitates the powder 31 carrying the light fine air-blown particles into the space 37 above the powder mass, leaving the heavier particles within the powder mass.

10 The air passing through the opening 15 of the end 13 and over the end of the tube 30, draws these light fine air-blown particles upwardly through the tube 30 and thence outwardly from the device in the form of a spray.

15 It will thus be seen that the emitted dust contains only the fine air-blown particles and is, therefore, finer, more efficient and more economical than would be the case if the entire mass of powder containing both fine and large particles was blown in the form of a spray.

20 The modified form of my device illustrated in Figures 4 and 5 is similar to the device previously described, except that the upper end 33 of the tube 30 is closed and the tube 30 has an opening 39 through it in alignment with the opening 15 of the end 13. The lower end 40 of the tube 35 is bent horizontally. The operation of this device is similar to that described, except that the air-blown powder is forced outwardly through the opening 39 of the tube 30.

25 It is evident, therefore, that during the operation of my device the fine, light particles of the powder are automatically separated from the larger heavier particles, the full particles being emitted as a spray while the larger particles remain in the powder receptacle.

30 35 I do not limit myself to the particular size, shape, number, arrangement or material of parts as shown and described, as these are given simply for clearly describing the device of my invention.

What I claim is:

40 1. A dust spraying device comprising a casing having a small opening in one end, a powder container, air means between said casing and said container adapted to violently agitate a powder mass within said container, and air means adapted to remove powder from above said powder mass and emit it from the device in the form of a spray, said air means having an opening in alignment with said end opening of said casing.

45 2. A dust spraying device comprising a casing

having a small opening in one end, a plunger longitudinally movable within said casing, a powder container, and air means between said casing and said container whereby a movement of said plunger will violently agitate a powder mass 5 within said container and will remove powder from above said powder mass and emit it from the device in the form of a spray, said air means having an opening in alignment with said end opening of said casing.

10 3. A dust spraying device comprising a casing having a small opening therein, a powder container, air means within said casing adapted to force air into said powder mass causing a violent agitation thereof, and means within said casing 15 adapted to remove powder from above said powder mass during said agitation and to emit it from the device in the form of a spray, said air means having an opening in alignment with said end opening of said casing.

20 4. A dust spraying device comprising a casing having a small opening in one end; a longitudinally movable plunger within said casing; a powder container; a cover for said container having two openings therein; a tube passing through one of 25 said openings and terminating in the upper portion of said container, said tube having an opening in alignment with said casing opening; a second tube passing through the other container cover opening and connecting the space within 30 the casing between its end opening and said plunger with the lower part of said container and means for moving said plunger longitudinally forcing air from within said casing through said end opening and said second tube.

35 5. A dust spraying device comprising a casing having a small opening in one end; a powder container; a cover for said container having two openings therein; a tube passing through one of 40 said openings and terminating in the upper portion of said container, said tube having an opening in alignment with said casing opening; a second tube passing through the other container cover opening and connecting the interior of said casing with the lower portion of said container 45 and means for forcing air from within said casing through said end opening of said casing and said second tube.

WILLIAM H. ROSE.
